CLAIM

The ornamental design for an eyeglasses holder, as shown and described.

DESCRIPTION

FIG. 1 is a perspective view of an eyeglasses holder, showing my new design, illustrated holding a broken line pair of eyeglasses;

FIG. 2 is a perspective view of the eyeglasses holder, showing my new design, illustrated without eyeglasses;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings show environmental structure associated with the eyeglasses holder in a condition of use, and form no part of the claimed design.
